(57) **CLAIM**

The ornamental design for a load cell for a scale, as shown and described.

DESCRIPTION

FIG. 1 is a perspective view of a part of the scale, namely a load cell, according to an embodiment of the present invention;

FIG. 2 is a typical side view, except the top and bottom plan views;

FIG. 3 is a top view thereof; and,

FIG. 4 is a bottom view thereof.

FIG. 1 shows in phantom a piece of cable that may be attached to the part of the scale in operation. The cable forms no part of the claimed design.
